UNITED STATES PATENT OFFICE.

BENJAMIN H. CLOWES, OF NEW YORK, N. Y.

TROUSERS-STRETCHER.

SPECIFICATION forming part of Letters Patent No. 380,550, dated April 3, 1888.

Application filed July 30, 1887. Serial No. 245,728. (No model.)

To all whom it may concern:

Be it known that I, BENJAMIN H. CLOWES, a citizen of the United States, and a resident of New York, in the county of New York and

5 State of New York, have invented certain new and useful Improvements in Stretching Devices for Trousers, &c.; and I do declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 Figure 1 of the drawings is a representation of this invention, and is a side view. Fig. 2 is a vertical longitudinal section. Fig. 3 is a top view. Fig. 4 is a detail.

The invention is an improved device for 20 stretching the legs of trousers, so as to prevent or remedy the bagging at the knees and wrinkling at the back of the leg opposite the knee; and it consists in the construction and novel combination of parts, as hereinafter set forth.

25 Referring to the drawings by letter, A designates a roller, having the pins *aa* secured eccentrically in its ends at corresponding points.

B is a lever-bar standing at right angles from the center of said roller at right angles to the 30 line joining the axes of said pins and the axes of the roller, and C is a catch on the outer surface of said bar adjoining the roller.

D is a roller or rounded bar somewhat longer than the roller A, and *dd* are eyes secured to 35 the side of said roller D near its ends, which form bearings for the pins *aa*, the eyes being usually cut or opened adjacent to their stems for facility of engaging the pins therein. The roller A also can be made relatively longer in 40 proportion to the roller D by this construction and incur no liability of disengaging therefrom laterally.

45 E E are stops secured to the side of the roller A, which bear against the roller D when the eccentric-pins are at or near their farthest point from the roller D.

F is a roller similar to the roller A and having the pins *ff* secured eccentrically in its ends. G is a locking-lever standing from the 50 center of the said roller at right angles to the line running from the axes of the pins *ff* to the axes of the roller.

H is a fulcrum rise or abutment to engage the end of the bar B, said rise or bearing being on the inner side of the locking-lever adjoining the roller F.

55 I is a roller or rounded bar similar to the roller D, and *ii* are eyes secured to the side thereof and forming bearings for the pins *ff*. The eyes may be cut similarly to the eyes *d*, 60 for the purpose of more easily engaging the pins *f*.

J J are stops secured to the roller F, acting against the roller I, and in all respects similar to the stops E. The rollers A D and F I form 65 clamps.

The method of using the device is as follows: The trouser-legs are placed between the rollers A and D, which rest thereon a suitable distance above the knee, and the bar B is turned 70 into position to make the rollers bind on the legs. The rollers F and I are similarly placed on the legs a distance below the former rollers slightly less than the combined length of the bar B, and the distance to the fulcrum-abutment H, which is raised with the locking-bar G until its end engages the end of the bar B. The locking-lever G is then turned down 75 against the bar B, and its end is engaged by the catch C of said bar, so that the leg is 80 stretched and held extended between the two pairs of rollers.

The pairs of rollers may be set closer together or farther apart, as it may be desired, to stretch the trousers more or less. When 85 the abutting fulcrum H and bar B are brought into line, the eccentric journals of the rollers A and F are so turned in their bearing as to cause the said rollers to bear on the cloth between the pairs of rollers.

90 Having described my invention, I claim—

1. The herein-described device to stretch the legs of trousers, composed of the roller A, having the eccentric-journal pins in its ends, the lever-bar B, secured to said roller, 95 the catch C, the roller D, having the eyes *d* secured thereto, the stops E, the roller F, provided with the eccentric-journal pins *f*, the roller I, having the eyes *i* secured thereto, the locking-lever G, the fulcrum H, and the stops J, substantially as specified.

2. In a device to stretch the legs of trousers, the combination of the two pairs of rollers, whereby the leg is held at different parts

thereof, the lever and fulcrum secured to a roller of one pair, and the lever-bar secured to the corresponding roller of the opposite pair, and having a detent upon it to hold the 5 end of the lever attached to the first pair of rollers when the same is pressed down, substantially as specified.

In testimony whereof I affix my signature in presence of two witnesses.

BENJAMIN H. CLOWES.
